UNITED STATES PATENT OFFICE.

JOHN M. JOHNSON, OF KANSAS CITY, KANSAS, ASSIGNOR TO THE UNITED STATES
AUTOMATIC FIRE ALARM COMPANY, A CORPORATION OF MISSOURI.

THERMAL CIRCUIT-BREAKER.

1,179,107.

Specification of Letters Patent. Patented Apr. 11, 1916.

Application filed July 2, 1913. Serial No. 777,065.

To all whom it may concern:

Be it known that I, JOHN M. JOHNSON, a citizen of the United States, residing at Kansas City, in the county of Wyandotte 5 and State of Kansas, have invented certain new and useful Improvements in Thermal Circuit-Breakers, of which the following is a specification:

This invention relates to improvements in 10 thermal circuit-breakers designed for use more particularly in connection with fire alarm apparatus where the circuit-breakers are located in places where a fire, if occurring, will cause a sufficient rise in temperature to operate one or more of the circuit-breakers before the fire can gain uncontrollable headway.

In order that the invention may be fully understood, reference will now be made to 20 the accompanying drawing forming a part of this specification, with the understanding, however, that while in the drawing there is shown a practical embodiment of the invention, the structure illustrated is susceptible 25 of changes and modifications so long as the salient features of the invention are retained and the result aimed at is obtained.

In the drawing: Figure 1 is a broken elevation partly in section of a circuit breaker constructed in accordance with my invention. Fig. 2 is a central vertical section on line II—II of Fig. 1. Fig. 3 is an enlarged broken section of the upper portion of the circuit-breaker taken on the 35 plane of line II—II of Fig. 1. Fig. 4 is a detail side elevation partly in section of certain elements employed in carrying out the invention. Fig. 5 is an inverted plan view of the device. Fig. 6 is a detail side elevation of a bell-shaped member and one of the 40 circuit terminals carried thereby.

1 designates a basic member made, preferably, in the form of a ceiling rosette from insulated material, such, for instance as porcelain. Said basic member 1 has an extension 2, containing a threaded-socket 3 held in said extension 2 by a conducting plate 4.

5 designates a disk of insulating material arranged within the socket member 3 and 50 abutting the conducting plate 4, against which it is held by a screw 6, extending into the basic member 1 and threaded into a second conducting plate 7. Screw 6 extends

through a large opening 8 in the conducting plate 4, to avoid contacting the latter.

55

9 designates a bell-shaped element of insulating material, preferably glass, carrying two circuit terminals 10 and 11. The bell-shaped element 9 is open at its large end and closed at its small end, which latter has affixed thereto a block of insulating material 12, incased in a threaded sleeve 13 adapted to be screwed into the socket 3. Socket 3 and sleeve 13, are formed of conducting metal to constitute part of a path, herein-after described, between the conducting plates 4 and 7.

60

One end of terminal 10, extends through the closed end of the bell-shaped element 9 and the block 12 from which latter it projects as disclosed by Fig. 3, to contact the screw 6. One end of the circuit terminal 11 passes through the closed end of the bell-shaped element 9, bends backward through the block 12 and engages the metal sleeve 70 13. The free ends of the circuit terminals 10 and 11 are connected by a fusible element 14 inclosed in a glass or other suitable receptacle 15. Said fusible element 14 consists, preferably, of an alloy of lead and 75 mercury proportioned to melt at the desired temperature. By placing the fusible element 14 in the receptacle 15, said fusible element, on melting, falls in a body from the terminals 10 and 11 and thus insures a clean 80 85 breaking of the circuit.

16 and 17 designate binding-screws threaded into the conducting plates 4 and 7, to receive the ends of wires 18 and 19, respectively, constituting part of a normally 90 closed circuit, such, for instance as disclosed in my copending application, filed Oct. 28, 1912, Serial No. 728,097.

The basic member 1 is provided with a housing 20, to protect the glass bell-shaped 95 member 9 from breakage. Said housing 20 is secured to the basic member 1, by a setscrew 21, and is of a size and shape to inclose the bell-shaped element 9, the lower end of which, like the lower end of said 100 apron is left open, so that heated gases may freely circulate around the fusible member 14. The path of the current is through conducting plate 4, socket 3, sleeve 13, terminal 11, fusible element 14, terminal 105 10, screw 6, and the conducting plate 7.

When used in connection with a fire-alarm system, the circuit-breakers are placed in any convenient position, usually at or near the ceiling of the room to be protected, so that heated air or gases of combustion arising from a fire will reach the fusible element and by melting the same break the circuit between the terminals 10 and 11 and thereby transmit an alarm to a central or sub-sta-
10 tion.

The devices can be made at small cost and of sufficient accuracy for the purpose of the invention, or even should the fusible elements 14 vary a degree or two from accuracy, it is of no moment since they may be arranged to break the circuit at a temperature far below that of a fire, and yet sufficiently above any temperature conditions to prevent the opening of the circuit except in
15 the event of a fire, which latter event, if quite distant from the circuit breakers, will cause the same to respond long before the fire can gain material headway.

Should a fire occur it may destroy some
25 of the circuit-breakers even though the fire be put out before much damage is done, and under these circumstances said circuit-breakers are renewed with the greatest ease and at little cost, since it is only necessary to unscrew the sleeve 13 from the socket 3 and replace said sleeve with a new one containing the bell-shaped element 9, the terminals 10 and 11, and the fusible element 14 connecting said terminals.
30
35 Having thus described my invention, what

I claim and desire to secure by Letters Patent is:

1. In a device of the character described, a basic member, a threaded socket carried by said basic member, a plug screwed into said socket, a bell-shaped apron of insulating material open at one end and closed at its opposite end, said closed end being fixed in the plug, circuit terminals spaced apart and carried by said apron, and fusible means electrically-connecting said circuit terminals.
40

2. In a device of the character described, a basic member of insulating material, two conductors separated from each other and secured to said basic member, a metal socket secured to said basic member and communicating with one of the conductors, a plug of insulating material having a metallic threaded sleeve removably-engaging said metal socket, two circuit terminals carried by but spaced apart by said plug, the end of one of said terminals contacting said sleeve and the end of the opposite terminal projecting from the plug, a screw engaging one of the conductors and adapted to be abutted by
45 said projecting end of the circuit terminal when the sleeve is screwed into the plug, and fusible means electrically-connecting said circuit terminals.
50

In testimony whereof I affix my signature, in the presence of two witnesses.

JOHN M. JOHNSON.
